PORTABLE DOMESTIC IRONING MACHINE

Frederick M. Freis, Chicago, Ill., assignor to Conlon-Moore Corporation, Cicero, Ill., a corporation of Delaware

Application December 5, 1947, Serial No. 739,949

11 Claims. (Cl. 38—60)

1

This invention relates to ironing machines and has to do with a light weight readily portable ironing machine intended for domestic or home use.

My invention is directed to an ironing machine of the character stated, which is of exceptionally light weight and is of compact and sturdy construction, so as to be readily portable while occupying but little storage space and being long lived. Further, the machine of my invention comprises comparatively few parts, many of which may be formed as stampings, and may be produced at low cost. The roll is driven from a suitable motor, through a driving train comprising a terminal gear movable into and out of driving engagement with a gear or pinion fixed to the motor shaft, whereby the motor may run free of parts driven thereby in the ironing operation, when the roll is stopped in the intervals between the passage through the machine of articles being ironed. That is desirable as permitting free turning of the roll in either direction for positioning thereon of articles to be ironed, while also conserving electrical energy for driving the machine, when an electric motor is used. The roll driving train comprises means whereby the terminal gear and the motor shaft gear or pinion are held in pressure contact for driving the roll, and the pressure between the gears increases with increasing resistance to rotation of the roll. That is advantageous, particularly when friction gears are used, as preventing objectionable slippage between the gears and thereby assuring proper drive of the roll. Preferably, the machine comprises a roll and a cooperating shoe moved to and from the roll by a control lever. This lever has an inoperative position, toward which it is yieldingly urged, and an operative position, means being provided for automatically locking the lever in its operative position and readily releasing it, when desired, for movement to inoperative position. The lever, in its movement from its operative position to its inoperative position, and vice versa, moves the terminal gear of the roll driving train out of and into driving engagement with the motor shaft gear or pinion for driving and stopping the roll, with the advantages above mentioned. Further objects and advantages of my invention will appear from the detail description.

In the drawings:

Figure 1 is a plan view of an ironing machine embodying my invention, the shoe cover being partly broken away to show the mounting of the shoe and the roll being partly broken away and shown in section, to show the drive connection

2

between the roll and its shaft, the gear housing cover being shown in section;

Figure 2 is a fragmentary sectional view, on an enlarged scale, taken substantially on line 2—2 of Figure 1;

Figure 3 is a sectional view taken substantially on line 3—3 of Figure 1, certain parts being shown in elevation and certain other parts being shown partly in section and partly in elevation;

Figure 4 is a sectional view taken substantially on line 4—4 of Figure 3, on a reduced scale; and

Figure 5 is a sectional view taken substantially on line 5—5 of Figure 3.

The ironing machine of my invention comprises a base 10, oblong in plan, of appropriate width and length, conveniently formed as a sheet metal stamping of channel section both lengthwise and transversely, there being a cushion bead 11 of rubber or like suitable material applied over the edge of the depending flange of base 10. A frame 12, of approximately U shape and formed as a stamping of sheet or plate metal of suitable gauge, is secured to the top of the base 10 adjacent one end thereof in a suitable manner, conveniently by bolting. Frame 12 comprises an upwardly extending inner arm 13, which constitutes the inner wall of the gear housing, as will appear more fully presently, and an outer arm 14 connected to the inner arm by a bight or base element 15 which seats upon and is secured to base 10, conveniently by bolting. A bearing sleeve 16 extends inwardly from the upper portion of arm 13 of frame 12, in overlying relation to base 10. Sleeve 16 is provided, adjacent its outer end, with an outer circumferential flange 17 which seats against the arm 13. The sleeve 16 is also provided with a reduced extension or hub 18 fitting through a corresponding opening in arm 13 of frame 12, this hub 18 being threaded for reception of a securing nut 19 screwing thereon and bearing against the inner face of arm 13. Sleeve 16 is thus tightly secured to arm 13 so as to extend inward therefrom above the base 10, as noted.

A roll shaft 20 extends through sleeve 16 and is rotatably supported therein by a suitable bushing 21. Shaft 20 extends inwardly beyond sleeve 16 a substantial distance, in overlying relation to base 10 and has mounted thereon a roll 22. This roll 22 comprises a sheet metal cylinder 23 within which are secured suitably spaced flanged metal discs 24, 25, and 26. Disc 24 is provided with a suitable opening accommodating sleeve 16 and the disc 25 has secured thereto a relatively thick annulus 27 through which and disc 25 the shaft

20 passes. The forward end portion of shaft 20 is slabbed off at opposite sides, to provide a flattened finger 29 which extends through a corresponding opening in disc 26 and through a like opening in a relatively thick annulus 30 suitably secured, conveniently by spot welding, to disc 26. The finger 29 extends inward an appreciable distance beyond the annulus 30 and receives a cotter pin 31 inserted therethrough. As will be understood, the finger 29 fits snugly through the openings in disc 26 and annulus 30 and provides driving connection between shaft 20 and roll 22. A suitable pad 33 is secured about cylinder 23 of roll 22 and is provided with a cover 32, as is known. It will be clear, from what has been said, that the roll 22 is mounted on and secured to shaft 20 for rotation therewith.

A shoe shaft 34 extends through the arms 13 and 14 of frame 12 and is rockably mounted therein. A washer 35 is disposed about shaft 34 adjacent the inner face of arm 14 and a cotter pin 36 is secured through shaft 34 adjacent the inner face of washer 35. The washer 35 and cotter pin 36 cooperate with arm 14 to restrain the shoe operating shaft 34 against lengthwise outward movement, as will be clear. An L shaped control and shoe operating lever 38, to be referred to more fully later, is provided, one arm 39 thereof having an opening which receives the shoe shaft 34, the other arm 40 thereof extending along shaft 34 at the back of the latter and being connected to arm 39 by an outwardly bent element 41. Arm 40 is suitably secured to shaft 34, conveniently by bolting, there being a flat plate 42 set into shaft 34 adjacent the inner end of arm 40 to provide ample seating area therefor.

The shoe shaft 34 extends inward over base 10 in overlying relation thereto and is disposed below and in back of the roll shaft 20 substantially parallel therewith. A short distance from its inner end, the shoe shaft 34 is mounted in the upwardly extending arm of the angle bracket 44 secured to the under face of base 10, conveniently by bolting, with one arm 45 extending upward through a slot 46 in base 10 and receiving the shaft 34. A shoe supporting arm 48 of channel cross section, conveniently formed as a stamping from sheet or plate metal of suitable gauge, is loosely mounted at its lower end on shoe shaft 34, at the inner end portion thereof and adjacent arm 45 of bracket 44. The shoe supporting arm 48 is provided at each side thereof with an upwardly extending ear 50. The ears 50 receive a pivot pin 51 extending therethrough and through the rearwardly projecting arms of angle brackets 52 seating on and secured to a clamp plate 56, by screw studs and nuts 53 and 54, respectively, which also secure clamp plate 56 to the face plate of the shoe 55, which cooperates with the roll 22. The shoe 55 is of known construction and includes a resistor held against the face plate of the shoe by a clamp plate 56, through which the screw studs 53 pass, as is known. Since, as noted, the shoe 55 is of known construction, further description thereof is not necessary here. The pin 51 is restrained against endwise movement by suitable locking devices or snap rings 58 engaging in grooves formed in the pin 51 and disposed adjacent the ears 50 and the outwardly or rearwardly extending arms of the brackets 52.

A spring 60 is suitably secured, conveniently by bolting, in a transverse slot in shoe shaft 34, extending from the inner end thereof, the spring 60 being disposed within the shoe supporting arm 48. A headed screw 61 is inserted through the spring

60, adjacent the upper end thereof, and passes through an opening in the bight portion of arm 48, receiving on its outer portion an adjusting knob 62 threaded thereon and bearing against the bight portion of arm 48. A compression spring 63 is disposed about screw 61 and confined between spring 60 and the inner face of the bight portion or element of arm 48. From what has been said, it will be seen that when the shoe shaft 34 is turned clockwise, as viewed in Figure 5, the shoe 55 is moved rearward away from roll 22, and when shaft 34 is turned counter-clockwise, by swinging the lever 38 downward into its operative position shown in full lines, the shoe 55 is moved into cooperating relation to the roll 22 and is held in pressure contact with articles passing between the roll and the shoe by the spring 60. The screw 61 and the knob 62 provide means for adjusting the relation between arm 48 and spring 60, thereby adjusting the effective pressure exerted by spring 60 for holding the shoe 55 to the roll 22.

The frame 12 constitutes, in effect, the gear housing of the machine, as will appear more fully later. The roll shaft 20 extends across the frame 12 and is mounted at its outer end in a flanged bushing 65 mounted in the outer arm 14 of frame 12, as shown more clearly in Figure 3. A yoke 66 of inverted U shape is mounted on shaft 20 for swinging movement thereabout and depends therefrom. A spur gear 70, in the form of a flat disc, is fixed on the outer end of a hub 69, which is secured, conveniently by a cotter pin 71, to shaft 20, there being a washer 72 interposed between the inner end of hub 69 and nut 19. It will be clear, from what has been said, that the yoke 66 is swingably mounted on the shaft 20 for movement thereabout forward and rearward of the gear housing.

A shaft 74 is rotatably mounted in the lower end of yoke 66, in flanged bushings 75 carried thereby. A spur pinion 76 is mounted on the inner end of shaft 74, the inner end portion 74a of which is reduced and slabbed off to provide a flat seat for pinion 76 having an opening therein corresponding to this reduced end portion 74a of shaft 74. Pinion 76 is confined between the inner end of the corresponding bushing 75 and a lock member, in the form of a snap ring 77 engaging in a corresponding groove in end portion 74a of shaft 74. The pinion 76 meshes with a spur gear 78 mounted on a counter shaft 79 which is freely mounted in yoke 66 above shaft 74. The gear 78 is confined between the adjacent arm of yoke 66 and a snap ring 80 engaging in a corresponding groove in shaft 79 at the inner face of gear 80, this gear 78 meshing with the gear 70 secured on the roll shaft 20. A snap ring 81 engages in a corresponding groove in shaft 79 at the outer face of the outer arm of yoke 66 and, in cooperation with gear 78 and snap ring 80, restrains shaft 79 against endwise movement in either direction. The counter shaft 79 passes through the upwardly extending arms of a U shaped cross member 82 suitably secured, conveniently by spot welding, to the arms of yoke 66. It will be seen that the gears 70 and 78 and the pinion 76 together constitute a planetary gear train the gears and pinion of which are constantly in mesh, while permitting free swinging of the yoke 66 about the shaft 20 for a purpose to be described presently.

The outer end portion of shaft 74 is slabbed off from opposite sides to produce a reduced flat sided element 84. This element 84 fits snugly

through openings of corresponding size and shape in two washers 85 and 86 disposed at opposite sides of disc 87 of a main drive member or terminal gear 88. Disc 87 also has an opening therethrough which snugly receives element 84 of shaft 74 and is secured on element 84 by means of a headed screw 93 threaded into element 84, in cooperation with the washer 86 and an intervening lock washer 91. The main drive or terminal gear 88 also includes a relatively thick rim 92 formed of a tough elastic material, such as synthetic rubber, or a natural rubber, fitting tightly about the circumferential area of disc 88 and bonded thereto in a suitable manner. It will be understood, from what has been said, that when the main or terminal gear 88 is driven the roll shaft 20, and consequently the roll 22, is driven thereby through the planetary gearing above described.

An electric motor 94 of suitable type is disposed within the frame or gear housing 12 at the lower rearward portion thereof. Conveniently, the motor 94 is supported by means of threaded rods 95 and 96 secured therein, rod 95 being disposed at the upper rearward corner of motor 94 and rod 96 being disposed at the lower forward corner thereof. Two shouldered cylindrical nuts 97 are threaded on the upper rod 95 and disposed with their reduced portions seating in the lower portions of slots 98 opening upward through the arms of the frame or gear housing 12. Likewise, two shouldered cylindrical nuts 99 are threaded on the lower rod with their reduced portions engaging in forwardly opening slots in the upper portions of arms 101 of bracket 102 suitably secured, conveniently by bolting, to the base or bight element of gear housing 12. The motor 94 may be mounted in any suitable manner, though I prefer the mounting means shown as providing for removal and replacement of the motor with expedition and facility. As is shown more clearly in Figure 1, the motor 94 is spaced outward from the inner arm or wall 13 of the gear housing 12 and has a suitable fan or blower 103, of known type, secured on the inner end of its shaft 104. As will be understood, the fan 103 serves to cause circulation of cooling air over and about the motor 94.

The motor shaft 104 is provided at its other or outer end with a gear or pinion secured thereto. Conveniently the outer end portion of shaft 104 is provided with a plurality of generally lengthwise shallow grooves providing a pinion 106 suitable for frictional engagement with the elastic rim 92 of the main drive or terminal gear 88. The pinion 106 is disposed substantially in the plane of gear 88 so that by swinging the yoke 66 rearward into what may be termed a drive position, gear 88 may be brought into driving engagement with pinion 106 so as to be driven thereby, thus driving roll 22 from the motor 94. By swinging the yoke 66 forward into what may be termed its stop position, the terminal gear 88 may be disengaged from pinion 106 of the motor shaft 104, thus stopping the drive of the roll 22.

The arm 39 of the control and shoe operating lever 38 extends forward from shoe shaft 34 adjacent the inner arm or wall 13 of the gear housing 12. This arm 39 is offset inwardly at its forward portion 39a, which extends forward alongside the outer face of a latch plate 108. This plate 108 is suitably secured, conveniently by bolting, to the inner arm or wall 13 of the gear housing 12, spaced a short distance inward therefrom. Plate 108 extends upward above the raised

position of lever 38, indicated in dot-and-dash lines in Figure 5, and is provided, at its lower portion, with a downwardly and rearwardly extending slot 109 opening at its upper end through the forward portion of plate 108, this slot being of approximately L shape and being provided, at its rearward end, with an upward extension 110 of arcuate shape. A handle member 111 is pivoted, at 112, on arm 39 of lever 38, a short distance from the forward end thereof. The handle member 111 extends forward from lever 38 and is provided, at its forward end, with a reduced tang 112 on which is secured a gripping member 113. The member 111 is also provided with a downwardly extending finger 114, in the lower end of which is secured a reduced stud 115a of a shouldered latch pin 115 provided, at its inner end, with a reduced neck 116a having a head 116 of materially greater diameter than neck 116a (Figures 3 and 5). An angle stop member 117 is suitably secured, conveniently by spot welding, to the forward end of lever 38 and extends upward a short distance above the latter, being provided at its upper end with an inwardly extending finger 118. This finger 118 is disposed to contact a bumper 120, in the form of a ring or collar of rubber or other suitable material, disposed about an anchor post 121 secured to wall 13 of the gear housing 12 and projecting a substantial distance inwardly thereof. A tension spring 123 is anchored at its upper end to a post 124, secured to and projecting inward from inner wall 13 of gear housing 12, adjacent the upper rearward portion thereof. The spring 123 is anchored at its lower end to an angle member 125 secured in a suitable manner, conveniently by spot welding, to the inwardly offset forward portion 39a of arm 39 of the control and shoe operating lever 38. As will be understood, spring 123 urges the lever 38 upward from its operative full line position shown in Figure 5 to its raised inoperative position indicated in dot and dash lines. When the lever 38 reaches its latter position, finger 118 of angle member 117 contacts the bumper 120 and in cooperation therewith limits upward movement of the lever 38.

The lower arm 127 of angle member 125 extends outward from lever 38 and in front of the downwardly extending arm 128 of an L shaped leaf spring 129. The upper arm 130 of spring 129 seats upon the bight element of cross member 82 and is secured thereto in a suitable manner, conveniently by headed screws 131 passing through arm 130 of spring 129, cross member 82 and a plate 132, the screws 131 receiving nuts 133 threaded thereon. A tension spring 135 is anchored at its upper end to the inner end of post 121 and extends downward and rearward therefrom, with its lower end anchored to the cross member 82, conveniently by means of one of the screws 131. The tension spring 135 is effective for swinging the yoke 66 forward, as limited by contact of spring 129 with arm 127 of angle member 125, into its stop position, when the control and shoe operating lever is raised to its inoperative position.

Swinging of the yoke 66 to its stop position moves the terminal gear 88 out of driving engagement with the pinion 106 of motor shaft 104, thus stopping drive of the roll 22. When the lever 38 is swung downward into its operative position, arm 127 of angle member 125 swings the yoke 66 rearward, by means of leaf spring 129, in opposition to the tension spring 135. This rearward swinging of yoke 66 moves the rim 92 of terminal

gear 88 into engagement with pinion 106 of motor shaft 104 shortly before the lever 38 reaches its full lowered operative position. The further downward movement of lever 38 causes rearward flexing of leaf spring 129, which then becomes effective for yieldingly holding the rim 92 of terminal gear 88 in pressure contact with pinion 106 of motor shaft 104. That assures effective driving engagement of the terminal gear with the motor shaft pinion.

In the operation of the machine the roll 22 is driven clockwise, as viewed in Figure 5, the gear 18 is driven counter-clockwise, and the pinion 16 is driven clockwise, as indicated by the arrows. It will be seen that resistance to rotation of roll 22, during the ironing operation, reacts on the gear 18 so that the yoke 66 is thereby subjected to pressure tending to swing it rearward about roll shaft 20, this pressure increasing as the resistance to rotation of the roll 22 increases. That is advantageous as assuring increasing pressure contact between the rim 92 of terminal gear 88 and the pinion 106 of the motor shaft 104 in accordance with increasing resistance to rotation of roll 22, thereby guarding against objectionable slippage between the terminal gear and the roll shaft pinion. That is conducive to continuous and smooth operation of the machine.

In order to establish driving connection between the roll and the motor, when an article to be ironed has been properly positioned upon roll 22, the control and shoe operating lever 38 is swung from its raised inoperative position downward to its lowered operative position. When the lever 38 is in its full raised position, indicated in dot-and-dash lines in Figure 5, the neck 116a of pin 115 is in contact with the downwardly and forwardly inclined front edge portion 108a of the latch plate 108 above slot 109, portion 108a of plate 108 serving as a cam and cooperating with pin 115 for holding the handle 111 in position with the main or body portion thereof substantially aligned with portion 39a of arm 39 of the lever 38. By grasping gripping member 113, the handle member 111 is swung downward, carrying with it lever 38. In the downward movement of member 111, the reduced neck 116a of pin 115 enters the upper end of slot 109 and passes downward therein and then rearward, the neck 116a of pin 115 then moving upward into the extension 110 at the rearward end of slot 109. That occurs when the lever 38 has been moved into its full lowered operative position, in which it is then latched, the tension spring 123 being ineffective for disengaging the neck 116a of pin 115 from the upward extension 110 of slot 109 and returning lever 38 to its raised position. In order to stop the roll 22, the handle member 111 is swung upward, thus disengaging neck 116a of pin 115 from the upward extension 110 of slot 109 and moving it into the forward portion of this slot. That releases the lever 38 which may then be moved to its raised inoperative position by tension spring 123, this upward movement of lever 38 being controlled, if desired, by means of the handle 111, the neck 116a of pin 115 travelling upward along the forward edge of plate 108 in contact therewith. It will be seen that the movements of the control and shoe operating lever 38 are effective for moving the shoe to and from the roll and also for swinging the yoke 66 to drive position and stop position, so as to establish and disestablish driving connection between the roll and the motor

70
75

in accordance with movement of the shoe to and from the roll.

The frame or gear housing 12 is provided with a suitably formed cover 137 seating at its lower edge on base 10 and secured to the outer arm 14 of the frame or gear housing 12 by suitably disposed screws 138 threading into arm 14 and pads or blocks 139 secured thereto, conveniently by spot welding. Preferably, a reinforcing arm 140 of appropriate form, which may be an aluminum casting, extends between the inner and outer arms or walls 13 and 14 of the frame or gear housing 12, at the upper ends thereof, and is secured thereto in a suitable manner, conveniently by means of screws. This arm 140 guards against possible spreading apart of the upper ends of walls 13 and 14 of the gear housing and assures proper alignment of the parts carried thereby. The cover 137 is, of course, appropriately formed to enclose the gear housing and the parts carried thereby, including the arm 140. The cover 137 is provided, through its front wall, with a vertical slot 142 of sufficient extent to accommodate the movements of handle member 111 passing therethrough.

An insulating grommet 145, of rubber or other suitable material, is secured through an opening in base 10. The grommet 145 receives an electric cord 146 passing therethrough and beneath base 10, suitable connections being provided between the wires or conductors of cord 146 and the resistor of shoe 55 and the motor 94, as is known. A plug cap 147 is attached to the free end of cord 146, whereby the machine may be plugged in or connected to the local or house circuit.

My instant invention is, in certain respects, in the nature of an improvement over the ironing machine disclosed in my co-pending application for a portable domestic ironing machine with a friction drive, Serial No. 634,419, filed December 12, 1945, and now Patent No. 2,578,928 dated December 18, 1951.

It will be understood that changes in detail may be resorted to without departing from the field and scope of my invention, and I intend to include all such variations, as fall within the scope of the appended claims, in this application in which the preferred form only of my invention is disclosed.

I claim:

1. In an ironing machine, a rotatably mounted roll shaft and a roll secured on said shaft, a co-operating shoe movable to and from said roll, a yoke mounted on said roll shaft for swinging movement thereabout and depending therefrom, a gear secured on said roll shaft, a gear and a pinion carried by said yoke constantly in mesh with each other with the yoke gear constantly in mesh with said roll shaft gear, a terminal gear carried by said yoke having driving connection with said pinion, a motor having a pinion secured to its shaft disposed substantially in the plane of said terminal gear whereby the latter may be moved into and out of driving engagement with said motor shaft pinion by swinging said yoke toward and away from said motor shaft, and means operable independently of said motor for moving said shoe to and from said roll and swinging said yoke toward and away from said motor shaft effective for establishing and disestablishing driving connection between said terminal gear and said motor shaft pinion.

2. In an ironing machine, a rotatably mounted roll shaft and a roll secured on said shaft, a co-

operating shoe movable to and from said roll, a motor, a yoke swingable on said shaft, a constantly meshing planetary gear train including a primary member and a gear secured on said roll shaft with the remainder of the gear train carried by said yoke, the latter being movable to a drive position establishing driving connection between said motor and the primary member of the gear train and to a stop position disconnecting the primary member of the gear train from said motor, a control and shoe operating lever operable independently of the operation of said motor and connected to said shoe for moving it to and from said roll, and means actuated by said lever for swinging said yoke from its stop position to its drive position and vice versa responsive to movement of said shoe to and from said roll.

3. In an ironing machine, a rotatably mounted roll shaft, a roll secured on said shaft, a cooperating shoe movable to and from said roll, a motor having a shaft substantially parallel with said roll shaft, a pinion secured on said motor shaft, a gear secured on said roll shaft, a yoke swingable on said roll shaft toward and away from said motor shaft pinion, means carried by said yoke for establishing and disestablishing driving connection between said motor shaft pinion and said roll shaft gear comprising a terminal gear on said yoke movable thereby into and out of driving engagement with said motor shaft pinion, a control and shoe operating lever operable independently of the operation of said motor and connected to said shoe for moving it to and from said roll, means yieldingly urging said yoke away from said motor shaft pinion, and cooperating means carried by said lever and said yoke for moving the latter toward said motor shaft pinion and thereby moving said terminal gear into driving engagement with said motor shaft pinion in the movement of said shoe to said roll and releasing said yoke for movement away from said motor shaft pinion to a position disengaging said terminal gear from said motor shaft pinion in the movement of said shoe from said roll.

4. In an ironing machine, a rotatably mounted roll shaft, a roll secured on said shaft, a cooperating shoe movable to and from said roll, a motor, a yoke on said roll shaft swingable thereabout to a drive position and a stop position, means carried in part by said yoke for establishing and disestablishing driving connections between said motor and said roll shaft responsive to movement of said yoke to drive position and to stop position, means yieldingly urging said yoke toward stop position, a control and shoe operating lever operable independently of the operation of said motor and connected to said shoe for moving it to and from said roll, said lever having a lowered operative position and being yieldingly urged toward a raised inoperative position, cooperating means carried by said lever and yoke for moving the latter to drive position and releasing it for movement to stop position responsive to movement of said lever to operative position and to inoperative position respectively, and means for latching said lever in operative position.

5. In an ironing machine, a rotatably mounted roll shaft, a roll secured on said shaft, a cooperating shoe movable to and from said roll, a motor, means for establishing and disestablishing driving connection between said motor and said roll shaft comprising a yoke on said roll shaft swingable thereabout to a drive position es-

tablishing such connection and to a stop position disestablishing such connection, means yieldingly urging said yoke toward stop position, a control and shoe operating lever operable independently of the operation of said motor and connected to said shoe for moving it to and from said roll, said lever having a lowered operative position and being yieldingly urged toward a raised inoperative position, cooperating means carried by said lever and yoke for moving the latter to drive position under yielding pressure and releasing it for movement to stop position responsive to movement of said lever to operative position and to inoperative position respectively, and means for latching said lever in operative position.

6. In an ironing machine, a rotatably mounted roll shaft, a roll secured on said shaft, a cooperating shoe movable to and from said roll, a motor, means for establishing and disestablishing driving connection between said motor and said roll shaft comprising a yoke on said roll shaft swingable thereabout to a drive position establishing such connection and to a stop position disestablishing such connection, means yieldingly urging said yoke toward stop position, a control and shoe operating lever operable independently of the operation of said motor and connected to said shoe for moving it to and from said roll, said lever having a lowered operative position and being yieldingly urged toward a raised inoperative position, cooperating means carried by said lever and yoke for moving the latter to drive position and releasing it for movement to stop position responsive to movement of said lever to operative position and to inoperative position respectively, a cam plate adjacent said lever, and handle and latch means carried by said lever and cooperating with said plate for moving said lever to its lowered operative position and latching it in such position.

7. In an ironing machine, a rotating roll, a rockably mounted shoe shaft below and in back of said roll substantially parallel therewith, a shoe mounted on said shaft movable thereby to and from said roll, a motor, a fixed cam latch plate disposed forwardly of said shaft, a control and shoe operating lever secured to said shaft extending therefrom forward alongside said plate, said lever having a lowered operative position in which the shoe has been moved to the roll in cooperating relation therewith and a raised inoperative position in which the shoe has been moved away from the roll, said lever and plate having cooperating means for moving said lever to and releasably latching it in its lowered operative position, and means operable independently of the operation of said motor for establishing and disestablishing driving connection between said motor and said roll responsive to movement of said lever to its operative position and to its inoperative position respectively.

8. In an ironing machine, a rotating roll, a rockably mounted shoe shaft below and in back of said roll substantially parallel therewith, a shoe mounted on said shaft movable thereby to and from said roll, a motor, a fixed cam latch plate disposed forwardly of said shaft, a control and shoe operating lever secured to said shaft extending therefrom forward alongside said plate, said lever having a lowered operative position in which the shoe has been moved to the roll in cooperating relation therewith and a raised inoperative position in which the shoe has been moved away from the roll, a handle member piv-

oted on said lever for relative vertical movement and extending forward therefrom, said handle member and said plate having cooperating means for moving said lever to and latching it in its lowered operative position upon downward movement of the forward portion of said handle member relative to said lever and releasing said lever for upward movement upon upward movement of the forward portion of said handle member relative to said lever, and means actuated and controlled by said lever operable independently of the operation of said motor for establishing and disestablishing driving connection between said motor and the roll responsive to movement of said lever to its operative position and to its inoperative position respectively.

9. In an ironing machine, a rotating roll, a rockably mounted shoe shaft below and in back of said roll substantially parallel therewith, a shoe mounted on said shaft movable thereby to and from said roll, a motor, a fixed cam latch plate disposed forwardly of said shaft provided with a downwardly and rearwardly extending slot, a control and shoe operating lever secured to said shaft extending therefrom forward alongside said plate, said lever having a lowered operative position in which the shoe has been moved to the roll in cooperating relation therewith and a raised inoperative position in which the shoe has been moved away from the roll, a handle member pivoted on said lever for relative vertical movement and extending therefrom forward, a latch member carried by said handle member engageable in said slot of said plate effective in cooperation therewith for moving said lever to and latching it in its lowered operative position and disengageable from said plate for releasing said lever for upward movement to its raised inoperative position, said latch member being engaged with and disengaged from said plate by vertical movement of said handle member in one direction and in the opposite direction respectively relative to said lever, and means operable independently of the operation of said motor for establishing and disestablishing driving connection between said motor and said roll responsive to movement of said lever to operative position and to inoperative position respectively.

10. In an ironing machine, a rotating roll and a cooperating shoe movable to and from said roll, a motor having a drive shaft and a pinion fixed thereon, a gear train having permanent driving

connection with said roll comprising a terminal gear movable into and out of driving engagement with said pinion, a control and shoe operating lever operable independently of said motor movable to an operative position and an inoperative position effective for moving said shoe to and from said roll respectively, means for holding said lever in operative position, means for holding said lever in inoperative position, and means actuated by said lever for moving said terminal gear into and out of driving engagement with said pinion responsive to movement of said lever to operative position and to inoperative position respectively.

11. In an ironing machine, a rotating roll and a cooperating shoe movable to and from said roll, a motor having a drive shaft and a pinion fixed thereon, a gear train having permanent driving connection with said roll comprising a terminal gear, said gear and pinion having relative movement into and out of driving engagement, a control and shoe operating lever movable to an operative position and an inoperative position effective for moving said shoe to and from said roll respectively, means for holding said lever in operative position, means for holding said lever in inoperative position, and means actuated by said lever for causing relative movement of said gear and pinion into and out of driving engagement responsive to movement of said lever to operative position and to inoperative position respectively.

FREDERICK M. FREIS.
